RANGE LIGHT REFLECTOR SHIELD

William Richard Crawford, Park Hills, Ky., assignor to Avco Manufacturing Corporation, Cincinnati, Ohio, a corporation of Delaware

Application January 31, 1950, Serial No. 141,481

7 Claims. (Cl. 240—2)

1

The present invention relates to an illuminating reflector located adjacent to a light source and relates more particularly to a reflector shield for attachment to the backguard of a cooking range whereby the shield not only reflects light from a source of illumination but also acts as a cover plate for shielding electrical units, such as fuses, located within the backguard.

It is an object of the present invention to provide a light reflector which is very simple in construction, consisting of a unitary piece of decorative material which is releasably secured to the backguard or backsplash of a range. It is another object of the present invention to provide a unitary reflector shield which serves the dual purpose of reflecting light from an associated light source and acting as a cover plate for shielding fuses or other electrical units positioned within the backguard.

It is well known by those skilled in the art that electrical fuses have on numerous occasions exploded during an electrical overload period. For this reason laws have been passed in various localities in the interest of fire prevention requiring that the fuses be shielded and not exposed in any way to combustible materials, such as the floor of the ordinary dwelling house. With this requirement in view, it will be apparent that the reflector shield of the present invention affords a simple and economical means for shielding the fuses as well as providing a simple reflector of light for illuminating the top cooking surface of the range.

Another advantage of the present invention is that it facilitates the location of electrical fuses in the backguard of an electric range and eliminates the necessity for unsightly supplementary cover plates for shielding the fuses as required by law.

From the viewpoint of those manufacturing and selling electrical ranges as well as the ultimate consumer, a particular advantage of the present invention is that it provides a light reflector shield which is particularly decorative and an efficient light reflector while eliminating light standards of the prior art type.

Another advantage of the present invention is that it may be attached to and removed from the associated backguard without the necessity of manipulating screws, bolts or similar attachments. This is obviously a very appealing feature, particularly in the American home where the lady of the house has assumed such a large responsibility for the maintenance and operation of household equipment. From the view-

2

point of the manufacturer this is also an important advantage in that it facilitates assembly of the range and cuts manufacturing costs.

A reflector shield made in accordance with the present invention has the additional advantage of requiring no welding, brazing or similar joining of components, but instead is made from a unitary piece of material. The present device also lends itself readily to a wide variety of decorative treatments with little additional cost and thus facilitates changes of the models produced by appliance manufacturers.

The novel features that are characteristic of the invention are set forth in the appended claims; the invention itself, however, both as to its organization and assembly, together with additional objects and advantages thereof, will best be understood from the following description of a specific embodiment when read in conjunction with the accompanying drawings, in which:

Figure 1 shows a front elevational view of a portion of the backguard of a range showing a reflector shield secured thereto for reflecting light from an associated source of illumination while simultaneously covering a pair of fuses; and

Figure 2 is a vertical sectional view taken on plane 2—2 of Figure 1 showing a portion of the backguard having the reflector shield in assembled relationship therewith and also showing in phantom lines an intermediate position of the shield assumed in the course of its removal from and assembly with the backguard.

Figure 3 is a partial cross sectional view of the rear portion of a reflector shield of modified construction.

As shown in the attached figures the structure of the present invention comprises a reflector shield 1 releasably secured to a range backguard, generally designated 2, by means of a plurality of spring clips 3. In its assembled position on the backguard of the range, the reflector shield is disposed adjacent to a light source 4 so as to reflect light therefrom downwardly onto the vertical face 5 of the backguard as well as the top cooking surface of the range (not shown).

Rotatably secured to face 5 of the backguard is a plurality of control switches 6 which are provided for the control of associated electrical heating elements in a manner well known in the art. For decorative purposes a supplementary face plate 7, bearing a timer 8 and other control switches 9, may be secured to face 5 of the backguard. The light reflected from source 4 by reflector shield 1 facilitates the ready manipula-

tion of the controls secured to the backguard as well as cooking on the range.

For illustrative purposes the light source 4 is shown to be a fluorescent light tube held in position by a pair of electrical brackets 10 secured to face 5 of the backguard. The present invention also comprehends the provision of other types of light sources such as conventional incandescent type bulbs.

A pair of electrical fuses 11 are held by sockets 11a attached to bracket 11b within the backguard in such a position as to be flush with or below its top face 12. These fuses are shielded or covered by reflector shield 1 when the reflector shield is attached to the backguard. As will be discussed more fully hereinafter, fuses 11 are very accessible through opening 12a formed in face 12 and may be removed and installed easily by the removal of the reflector shield. It is noteworthy that, as shown in Figure 1, the fuses are protected and completely surrounded by metal as well as being out of sight when the reflector shield is attached to the backguard.

Face 5 of the backguard is planar for the most part as indicated in Figure 2. However, face 5 is curved outwardly at its top portion adjacent to face 12 with the exception of that region which the light source 4 spans, this region being coplanar with the major portion of face 5. The curved forwardly extending surface is designated by reference numerals 13. Thus, curved surface 13, in conjunction with the light source 4, tends to create a more or less uniformly forwardly projecting region along the upper edge of the backguard.

A plurality of rectangular openings 14 is provided in face 12 of a size corresponding to and for the purpose of retaining spring clips 3. These clips are shown in side view in Figure 2 in their normally expanded position (full lines) and also in their collapsed position (phantom lines) which is assumed when the reflector shield is assembled to or removed from the backguard. The spring clips define at their upward ends projecting ears 15, the rearmost ears engaging the rear portion of the reflector shield in a manner and for a purpose to be described hereinafter.

It is noteworthy that the configuration of spring clips 3 is such that there is no tendency, when in their normal position, to work out of openings 14, but instead through a camming action on the edges of the openings they tend to remain retracted within the backguard.

Reflector shield 1 is unitary, being fabricated from a single sheet of metal to provide a flat top surface 16 and curved forward portion 17 through its full length. A turned flange 18 is formed along the rear edge of the shield for its full length. The remaining edges of the reflector shield are simply flanged as indicated at 19 in Figure 1. The simple flanges provided at the ends of the reflector shield space the shield slightly away from the backguard as indicated at 20. In addition the simple flanges, in conjunction with the adjacent spring clips aid in centralizing the shield on the backguard.

The curved forward portion 17 is reduced in extent as indicated at 21 for the entire length of the light source 4 to facilitate the reflection of light rays from the source downwardly on to the controls and work surface of the range.

In order to assemble the reflector shield on the backguard of the range turned flange 18 is engaged with the rearmost ears 15 of spring clips 3. The shield is then pulled forward, deflecting the

spring clips as indicated in phantom lines in Figure 2; when so deflected, edge 22 of the reflector shield will be in position to clear curved portions 13 of the backguard and the reflector shield will pass through the position shown in phantom lines to the assembled position shown in full lines.

In the assembled position, the reflector is drawn into intimate engagement with the backguard by the spring clips which tend to expand and force the reflector shield toward the rear. Movement of the shield to the rear is limited, however, by the engagement of curved portion 17 of the shield on curved portions 13 of the backguard. Thus the reflector shield is in effect releasably hooked onto the backguard with its plane face 16 held parallel to surface 12.

As shown in Figure 2, the reflector shield is spaced from light source 4 and is ideally positioned for the reflection of light onto face 5 of the backguard and other portions of the range. It should be noted that the reflector shield acts as a cover plate for fuses 11 which are readily accessible by the simple and rapid removal of the shield by pulling it forward and raising it so as to clear curved portions 13 of the backguard.

It will be appreciated by those skilled in the art that this reflector shield represents a very substantial manufacturing improvement in that it may be easily and economically fabricated from a single sheet of material. The shield, although preferably made of chromium plated steel, can be made of plastic or even of glass if such is considered desirable.

It will also be understood that the simple construction of the shield lends itself readily to a wide variety of decorative configurations such as coined grooves (not shown) and other effects which are easily produced by moulding and stamping. This is an obvious advantage in the manufacture of articles, the appearance of which must be changed from year to year to meet the insatiable demand of the consuming public for eye-appealing appliances of novel design.

As illustrated in particular in Figure 1, the reflector shield when assembled to the backguard does not project any significant distance above face 12. The improvement in the appearance of the backguard and shield assembly is believed to be manifest in contrast to the conventional light fixtures which project above the top surface of the backguard proper.

The herein disclosed invention has been described with particular reference to its use on an electric cooking range. It should be understood, however, that the construction can be applied to a very wide variety of appliances wherein it is desired to provide an economical, simple, decorative reflector shield. It is particularly useful in an application where the reflector shield performs the additional function of acting as a cover plate over electrical fuses or like units which must be readily accessible but preferably kept out of sight.

A modified construction is shown in Figure 3 which eliminates the need for spring clips 3 by the provision of a rearwardly and downwardly extending rear portion 23 of the shield. Portion 23 extends over the rear 2a of backguard 2 and is formed to define a plurality of indentations or "dimples" 24 for engagement with corresponding dimples or recesses 25 provided in the rear wall of the backguard. The modified shield has a shallow, modified U-shaped cross section which conforms at its ends with the configuration of the backguard.

A reflector shield constructed in accordance with Figure 3 is held in engagement with the backguard by the resilience of the reflector shield itself. In other words, when the shield is assembled with the backguard, it is sprung sufficiently to permit the passage of dimples 24 into recesses 25 thereby producing slight internal stresses within the shield which hold it in clamped engagement with the backguard.

The modified shield is assembled to the backguard by first being engaged with the forwardly projecting curved surfaces 13 thereof. Thereafter, rear portion 23 of the shield is swung downwardly until the "dimples" 24 are brought into engagement with recesses 25. This engagement centralizes as well as holds the shield in position.

It will be obvious to those skilled in the art that the modified construction has the advantage of eliminating spring clips 3 and the necessity for providing openings 14 in face 12 of the backguard.

Having described a preferred embodiment of my invention, I claim:

1. In combination with an appliance, a hollow backguard provided with forwardly convexly curved horizontal end portions near the top of its forward face; a light source secured to the forward face between the curved portions; an elongated reflector shield conforming at its ends to the curved configuration of the top portion of the backguard and provided with a curved forward portion in reflecting relationship with said light source, and electric fuses disposed within the backguard, said backguard being formed to define an opening through which said fuses may be removed, said opening being positioned adjacent said light source for coverage by said reflector shield when assembled with said backguard.

2. In combination with an appliance, a backguard with a top face and a front face, a light source secured to the front face, fuses within the backguard accessible through an opening formed within its top face, the top face of said backguard being formed to define separate openings spaced from the fuse opening, resilient means disposed within the separate openings, a cover removably disposed over the top face having a curved forward portion in light reflecting relationship with said light source and a planar rear portion covering the fuse opening, said resilient means engaging said cover and drawing it against the top and front face of the backguard in covering relationship above said fuse opening and in light reflecting relationship with said light source.

3. In an electric range, a backguard having a top and a substantially vertical front face the upper end portions of which are outwardly and convexly curved forming horizontally extending projections, a light source secured to the vertical front face between the curved end portions; electric fuses disposed within said backguard adjacent said light source, said fuses being accessible through an opening formed within the top of said backguard; a unitary reflector shield having an elongated planar portion for covering the fuse opening and a curved forward portion corresponding generally to the shape of the convexly curved upper end portions of said backguard; a flange along the edge of said shield remote from the forward portion; said backguard being formed to define a plurality of openings in its top face; and

a plurality of spring clips disposed within the openings in said backguard, ears on said spring clips projecting outwardly from said backguard for engaging said flange of said reflector shield, said springs exerting on said reflector shield rearwardly directed forces for drawing the curved forward portion of said shield into intimate engagement with the curved upper end portions of said backguard in position to reflect light from said light source and to cover the fuse opening.

4. A resilient unitary reflector shield in combination with a range having an upstanding backguard with rear and top faces and a forward face to which is secured a source of illumination and having fuses within the backguard accessible through an opening in its top face adjacent the source of illumination, the shield comprising an elongated planar portion covering the fuse opening and conforming at its ends with the shape of the backguard so as to embrace its front and top faces, the forward portion of said shield being curved forwardly and downwardly to partially encompass the source of illumination and to reflect light therefrom, and resilient means releasably connecting the rear portion of said reflector shield to the backguard.

5. Apparatus as defined in claim 4 in which said resilient means comprises a plurality of springs resiliently and releasably engaged with the backguard and said shield whereby rearwardly directed forces are imposed on said shield drawing it into intimate engagement with the front of the backguard.

6. Apparatus as defined in claim 4 in which said means comprises inwardly projecting dimples formed in the rear portion of said shield and resiliently engaged with recesses formed within the rear face of the backguard.

7. In combination with an appliance, a hollow backguard provided with forwardly, convexly curved horizontal end portions near the top of its forward face; a light source secured to the forward face between the curved portions; an elongated reflector shield conforming at its ends to the curved configuration of the top portion of the backguard and provided with a curved forward portion in reflecting relationship with said light source; and a circuit-interrupting device disposed within the backguard, said backguard being formed to define an opening through which said circuit-interrupting device is accessible, said opening being positioned adjacent said light source for coverage by said reflector shield when assembled with said backguard.
